UNITED STATES PATENT OFFICE

135,022

DESIGN FOR A COMBINED FLATIRON AND LAMP HOUSING

Harris D. McKinney, Bucks County, Pa., assignor
to Proctor & Schwartz, Inc., Philadelphia, Pa.,
a corporation of Pennsylvania

Application March 10, 1942, Serial No. 106,142

Term of patent 14 years

To all whom it may concern:

Be it known that I, Harris D. McKinney, a citizen of the United States, residing in Bucks County, Pennsylvania, have invented a new, original, and ornamental Design for a Combined Flatiron and Lamp Housing, of which the following is a specification, reference being had to the accompanying drawing, forming part thereof, in which:

Figure 1 is a side elevational view of a combined flatiron and lamp housing showing my new design.

Fig. 2 is a front elevational view of the same.
Fig. 3 is a sectional view taken along line 3—3 of Fig. 1.

The dominant features of the design reside in the portions shown in full lines.

I claim:

The ornamental design for a combined flatiron and lamp housing, substantially as shown and described.

HARRIS D. McKINNEY.
